[57] ABSTRACT

A priority circuit for passing in accordance with a given priority one of a plurality of interrogation signals coming from a number of lines to an output, said number of lines being divided in a number of different groups of lines, said circuit comprising means for dealing with interrogations within one group in accordance with a predetermined priority, there being provided means for processing cyclically the groups. The circuit comprises for this purpose a 1-out-of-(n+2) position device in which n is the number of lines of each group and the $(n+1)$ th position is provided for activating the group by the preceding group, whilst the $(n+2)$ th position is provided for setting the group into the rest position from a next following group (FIG. 3).

CYCLIC GROUP PROCESSING WITH INTERNAL PRIORITY

The invention relates to a priority circuit for transferring one of the signals coming through a plurality of lines in accordance with a given priority to an output, said number of lines being arranged in a number of different groups of lines, in which in each group each interrogation signal and the inverse values of the interrogation signals of high priority in the group concerned are applied to inputs of a logical (NOT)-AND gate, whilst in addition for activating a group an input of each of said logical (NOT)-AND gates in the group is connected to the output of the preceding group.

Such a priority circuit is known (U.S. Pat. Specification No. 3,353,160). The known priority circuit is appropriate for transferring, in accordance with a given priority, to a common output, one of the interrogation signals coming through a great number of lines, for which purpose the lines of the interrogation signals are arranged in a number of groups. Inside each group a given priority is fixed for each incoming line. By means of said (NOT)-AND gates the interrogation signal is transferred to the output of the group associated with the line having an interrogation signal and having the highest priority in the group. In this known arrangement said groups are arranged in a number of priority levels, the output of a group of a lower level being connected to an input of a group of the superjacent level. If an interrogation signal can be passed in a group of lower level, this is indicated from the group of the superjacent level for which purpose an input of each logical (NOT)-AND gate of the group of said lower level is connected to the relevant output of said group of the superjacent level.

An important problem involved in the known arrangement resides in that interrogations of the lowest or lower priorities will never or almost never have their turn. If constantly interrogations of higher priority are made, they are invariably dealt with in priority so that the other interrogation cannot come through. This may give rise to inadmissible waiting times for interrogations of lower priority. The invention has for its object to provide a priority circuit in which this disadvantage is obviated. The priority circuit according to the invention is characterized in that in order to obtain a priority circuit in which the groups are dealt with in cyclic order of succession whilst the priority in one group is maintained, each group is provided with an additional (NOT)-AND gate, one input of which is connected to said output of the preceding group and further inputs of which are connected to terminals where the inverses of the interrogation signals are available, whilst in one group the output of each (NOT)-AND gate is connected to an input of $(n+1)$ inputs of a 1-out-of- $(n+2)$ position device, wherein n is the number of lines in one group, and for the adjustment of a rest position in which a group is blocked for interrogation signals the $(n+2)$ th input of the 1-out-of- $(n+2)$ position device is connected to the output of the next-following group. In the priority circuit according to the invention it is ensured that the groups of lines for interrogation signals per group are always handled in cyclic order of succession. It should be noted that a cyclic handling of interrogations, for example, by a shift register in which the interrogations are dealt with in the order of entry is known. However, there is no splitting into groups, in which the lines have priority in each group. In the priority circuit according to the invention the priority of the lines relative to each other is maintained apart from the cyclic handling of the groups. In this manner the interrogations are dealt with from a starting moment in a first group in accordance with priority, after which the interrogations of a next group are dealt with. If there are none, the next following group is scanned etc., until the first group is again reached. It is thus ensured that also the groups remote from the first group are regularly checked for interrogations. In practice it may be imagined that in a computer system interrogations for magnetic tape apparatus are handled in accordance with a given priority schedule; a second group may be adapted to receive interrogations for information exchange with a chart reading apparatus and the like, whereas a third

group is adapted to receive interrogations from the operator and the like. According to the present invention the operator may be sure that as soon as no interrogations for a magnetic tape is coming in and if the chart reading apparatus becomes operative at the presence of an interrogation, his interrogation will be dealt with after the interrogation in the group of chart reading apparatus is finished. An intermediate new interrogation for the magnetic tape apparatus is then not treated with priority. Only when the priority circuit has performed a cycle through all groups the first group is again checked. Apart from said example, many instances may be imagined in which such groups of interrogations have to be dealt with, for example, in communication systems.

It would be noted that in the circuit described both NOT-AND gates and AND gates may be employed, which is indicated herein by (NOT)-AND. Moreover, it should be noted that were NOT-AND gates may be used, NOT-OR gates may also be employed taking signal inversion into consideration, because as is known, from the book of Maley and Earle: "The logic design of transistor digital computers" 1963, pages 115 to 117, the NOT-AND and NOT-OR functions are dual ones.

The 1-out-of- $(n+2)$ position device may be formed by $(n+2)$ flip-flops, the setting inputs of which are connected to the outputs of said $(n+1)$ (NOT)-AND gates of the relevant group and to the said output of the next group, whilst the output of a flip-flop is connected to reset inputs of the other flip-flops in the group.

A very simple embodiment of the priority circuit according to the invention is obtained by having the 1-out-of- $(n+2)$ position device formed by a $(n+2)$ multiplet circuit having $(n+2)$ NOT-AND gates in series, the outputs of the NOT-AND gates, receiving the interrogation signals and the inverses thereof being connected to the inputs of the multiplet so that the multiplet takes over the signal condition of the outputs of said NOT-AND gates as a position of 1-out-of- $(n+2)$ positions.

A slightly different form consists in that if $(n+1)$ AND gates are used as input gates of a group the multiplet circuit is formed by NOT-OR gates.

The invention will be described more fully with reference to the drawing in which,

FIG. 1 is a first embodiment of a priority circuit according to the invention,

FIG. 2 is an example of a device in which the priority circuit according to the invention can be employed,

FIG. 3 is a further embodiment of a priority circuit according to the invention and

FIG. 4 is a slightly different embodiment of the circuit of FIG. 3.

For the sake of simplicity FIG. 1 shows three groups G_1 , G_2 and G_3 having each three interrogation lines G_{11} , G_{12} , G_{13} , G_{21} , G_{22} , G_{23} and G_{31} , G_{32} and G_{33} respectively, at which interrogation signals may appear. The priority circuit shown forms a ring in which the groups G_1 , G_2 , G_3 , G_1 , etc., have their turn cyclically, whilst the interrogation signals are dealt with in accordance with the priority in the group. In a group G_j an interrogation line G_{j1} has priority over G_{j2} , G_{j2} has priority over G_{j3} ($j=1, 2$ or 3). For this purpose the interrogation line G_{j1} of group G_j is connected to an AND-gate 11 and through an inverter 11a to AND-gates 12, 13 and 14; the interrogation line G_{j2} is connected to the AND-gate 12 and through an inverter 12a to the AND-gates 13 and 14, whereas the interrogation line 13 is connected to the AND-gate 13 and through an inverter 13a to the AND-gate 14. In a similar manner the groups G_2 and G_3 are arranged, which comprise the AND-gates 21...24 and 31...34 and the inverters 21a...23a and 31a...33a. Said AND-gates 14, 24 and 34 are the aforesaid additional AND gates provided for each group. The output of a preceding group is connected to all AND gates of a group; an input of the AND-gates 11...14 of the group G_1 is connected to the output Z_3 of the group G_3 preceding (in the ring) the group G_1 . An input of the AND-gates 21...24 of group G_2 is connected to the output Z_1 of the preceding group G_1 . An input of the AND-gates 31...34 of group G_3 is connected to the output Z_2

of the preceding group G_2 . Each group comprises a 1-out-of-($n+2$) position device S_1 , S_2 and S_3 respectively. In this case $n=3$ so that each group has a 1-out-of-5 position device. In this example a 1-out-of-5 position device S_1 is formed by five flip-flops. The group G_1 comprises the flip-flops $FF_{11}, FF_{12}, \dots, FF_{15}$, the group G_2 the flip-flops $FF_{21}, \dots, FF_{25}$ and the group G_3 the flip-flops $FF_{31}, \dots, FF_{35}$. The flip-flops FF_{j1} to FF_{j4} are connected at their set input to the output of the respective AND-gates $j1$ to $j4$. The set input of the $(j+5)$ th flip-flop FF_{j5} is connected to the output of the next following group. Thus: flip-flop FF_{15} is connected to the output Z_2 of group G_2 ,

flip-flop FF_{25} is connected to the output Z_3 of the group G_3 and

flip-flop FF_{35} is connected to the output Z_1 of group G_1 .

In order to operate as a 1-out-of-5 position device the outputs $U_{11}, U_{12}, U_{13}, U_{14}, U_{15}$ of the flip-flops $FF_{11}, \dots, FF_{15}$ are connected to reset inputs $r_{11}, r_{12}, \dots, r_{15}$ of each other. The same applies to the outputs $U_{21}, \dots, U_{25}$ and $U_{31}, \dots, U_{35}$ of the respective flip-flops $FF_{21}, \dots, FF_{25}$ and $FF_{31}, \dots, FF_{35}$ with their reset inputs $r_{21}, \dots, r_{25}$ and r_{35} respectively.

The operation is as follows. It is assumed that a signal present at a line represents a "1" value and a signal not present represents a "0" value. It is assumed that interrogation signals "1" appear at the lines G_{11} and G_{13} of group G_1 and the output Z_3 of group G_3 has a signal "1" (more detail hereinafter). In this case the AND-gate 11 is opened and provides a "1" signal at the set input of flip-flop FF_{11} . The AND-gate 13 remains closed despite the "1" signal at Z_3 and the line G_{13} because from the inverter $11a$ this gate receives a "0" signal, which is the inverse of the "1" signal at line G_{11} . The flip-flop FF_{11} thus gets into the "1" state, which becomes manifest by a "1" signal at its output U_{11} . Any "1" state of a further flip-flop of the group resulting from a previous treatment is erased from the output U_{11} of the flip-flop FF_{11} via a corresponding reset input r_{11} ($i \neq 1$) of the other flip-flop.

In this example during the treatment of an interrogation, in this case an interrogation due to the signal at line G_{11} , this interrogation signal has to remain available, since otherwise the interrogation signal of the line G_{13} will influence the process. With reference to FIG. 3 it will be described that conditions may be different. When in this example the interrogation for which the line G_{11} conveys the signal "1" is answered, this "1" signal disappears. If, as assumed, the line G_{12} does not pass a "1" signal, but the line G_{13} does, the gate 13 is opened and the flip-flop FF_{13} is set. The output U_{13} receives the "1" signal and the flip-flop FF_{11} , which was still in the "1" state, is reset to "0" via a reset input r_{11} from U_{13} . In this way interrogations are accomplished within one group in accordance with priority. If during the processing of an interrogation along line G_{13} an interrogation signal is received across G_{11} or G_{12} , the interrogation from G_{13} is first interrupted in this example and the interrogation of higher priority is first dealt with. The above applies in a corresponding manner to the other groups $G_{j+1}, \dots, G_m$, when they are activated via the output Z_j of the preceding group. If, for example, in group G_1 all interrogations are answered to, the AND-gate 14 is opened because all "0" signals of lines $G_{11}, \dots, G_{13}$ via their inverters $11a, \dots, 13a$ together with the "1" signal of line Z_3 have a "1" value at the inputs of this AND-gate 14 . This means that flip-flop FF_{14} gets into the "1" state and "1" state of a further flip-flop in the group is reset to "0" via the output U_{14} through one of the reset inputs. Thus the line Z_1 has a "1" signal. This "1" signal passes to the next group, in this case G_2 , which can then be activated. At the same time the "1" signal of the line Z_1 is also applied to the input of the $(n+2)$ th=5th flip-flop FF_{35} of the preceding group, in this case G_3 . The flip-flop FF_{35} gets into the "1" state and across its output U_{35} the flip-flop FF_{34} , which was still in the "1" state, (it provided so far across the line Z_3 a "1" signal for activating the group G_1) is reset into the "0" state. Thus the group G_3 is in the rest position and the line Z_3 has a "0" signal, whereas the group G_1 is in the lowest priority position (FF_{14} is in the "1" state), from where group G_2 is activated via the line Z_1 .

Then interrogations in group G_2 are dealt with etc. If in the meantime interrogations are received in group G_1 or group G_3 , they are not dealt with because these groups are not activated via the line Z_3 or Z_2 respectively. Not until have all interrogations of group G_2 been dealt with, the line Z_2 will have a "1" signal, so that the group G_3 is activated, whereas the group G_1 gets into the rest position by means of the flip-flop FF_{15} . In this way all groups have their turn in cyclic order of succession so that no inadmissible waiting times will occur for groups far remote from the first group.

FIG. 2 illustrates schematically how a priority circuit PC according to the invention may be arranged in a system. $A_{11}, A_{12}, \dots, A_{1n}, A_{m1}, A_{m2}, \dots, A_{mp}$ are peripheral apparatus which may ask a communication with a computer C . When an interrogation A_{ij} comes in, a signal appears at the line G_{ij} concerned, connected to the priority circuit PC. The peripheral apparatus are connected to a gate P_{ij} ($P_{11}, P_{12}, \dots, P_{1n}, P_{m1}, P_{m2}, \dots, P_{mp}$). When the apparatus A_{ij} is released for a communication with the computer C , a release signal is applied to the relevant gate P_{ij} via the output U_{ij} of the priority circuit PC. Via this gate P_{ij} the peripheral apparatus A_{ij} is connected via a channel Ch , which is common to all peripheral apparatus, to the computer C .

FIG. 3 shows an embodiment of a priority circuit embodying the invention, which is formed as a whole of NOT-AND gates. It is indicated at the same time that the control of the circuit as a whole can be performed from a control part (not shown) of a computer through the lines OT and $1T$. The construction from groups G_{a-1}, G_a and $G_{a+1}, \dots, G_m$ and different number of lines in each group $G_{a-1}, \dots, G_a, G_{a+1}, \dots, G_{a+1,n}$ is practically similar to that shown in FIG. 1, where the AND gates are replaced by NOT-AND gates $a1, a2, \dots, a4, \dots, e1, \dots, en$ and the $(n+2)$ NOT-AND gates $b1, b2, \dots, b5, \dots, f1, f2, \dots, f(n+1)$. The inverters $11a$ etc., may be omitted by using the output signals of the NOT-AND gate associated with a given interrogation signal. There are added the inverters formed by the NOT-AND-gates $\dots, ca, c(a+1), \dots$. There are furthermore the NOT-AND-gates $\dots, da, d(a+1), \dots$ which have both a $1T$ line and the output $\dots, Z_{a+1}, Z_{a+2}, \dots$ of a next group as inputs.

The operation is mainly the same as that of the priority circuit of FIG. 1, be it that the multiplets formed by the series combination of NOT-AND-gates $b1, b2, \dots, b5$ and $f1, \dots, f(n+2)$ respectively have a slightly different operation than the flip-flops: if an interrogation signal "1" is present on the line G_{a2} and not at the same time on the line G_{a1} and if the group G_a can be activated by a "1" signal from the line Z_{a-1} of the preceding group and a command "1" is received from the control part (not shown) via the line OT , the NOT-AND-gate $a2$ will provide a "0" signal at the output. The other NOT-AND-gates $a1, a3$ and $a4$ have a "1" signal at the outputs. For the multiplet having the NOT-AND-gates $b1, \dots, b5$ this means that: $b1$ receives inter alia a "0" and a "1" signal from the NOT-AND-gate $a2$ and $a3$ respectively. This means that this NOT-AND-gate $b1$ has a "1" signal at its output U_{a1} . The same applies to the NOT-AND-gates $b1, b4$ and $b5$. Only the NOT-AND-gate $b2$ receives a "1" signal at all its inputs (the NOT-AND-gate da has also a "1" signal at its output because its inputs have a "0" signal) and has a "0" signal at the output U_{a2} . This "0" signal indicates the release of the interrogation receives via the line G_{a2} . The interrogation signal of the line G_{a2} need not remain present during the process because the command "1" from the line OT reappears only after the accomplishment of the whole interrogation or, as the case may be, a partial interrogation (to be interrupted at a suitable point), in order to apply any other interrogation signal or the same interrogation signal to the NOT-AND-gates $a1, \dots, a4$. When the group G_{a+1} gets into the lowest priority position, that is to say, when the output $U_{a+1,n}$ of the NOT-AND-gate $f(n+1)$ has a "0" signal, this "0" signal of the NOT-AND-gate $f(n+1)$, subsequent to inversion in the NOT-AND-gate $c(a+1)$ is applied as a "1" signal along the line Z_{a+1} to the next following group G_{a+2} for activating the same when a "1" signal is given via OT . At the same time this "1" signal is applied

through the line Z_{a+1} to the NOT-AND-gate da of the preceding group G_n . When from the line $1T$ a command "1" is received, this NOT-AND-gate da provides a "0" signal at its output. This "0" signal is applied to the $(n+2)$ th input of the multiplet, i.e., the output U_{as} of the NOT-AND-gate $b5$. This output U_{as} thus necessarily obtains a "0" signal and hence also all other outputs $U_{a1} \dots U_{a4}$ have a "1" signal. Thus the rest position of the multiplied is obtained and it is ready for operation when a "1" signal comes in through the line Z_{a-1} and a further "1" signal through the line OT .

FIG. 4 shows a variant of the embodiment of FIG. 3. As an example only one group G_1 is shown. This arrangement comprises as inverters the NOT-AND-gates (see FIG. 1) $a11, a12, a13$ for the formation of the inverted signals for the NOT-AND-gates $a1, a2, a3$ and $a4$. This has the advantage that outputs of the NOT-AND-gates $a1 \dots a4$ can be directly "OR"-ed with the connections between the NOT-AND-gates $b1, b2 \dots b5$ of the 1-out-of- $(n+2)$ multiplet so that (cf. FIG. 3) a number of inputs (diodes) are economized. It should be emphasized that other 1-out-of- $(n+2)$ position devices may be designed suitable for use in the arrangement according to the invention.

What is claimed is:

1. A computing device comprising a priority circuit for transferring one of a plurality of interrogation signals coming in from a number of lines in accordance with a given priority, in a cyclic order of succession while maintaining the priority in a group, said number of lines being arranged in a number of

different groups of lines, in which each interrogation signal and the inverses thereof of higher priority in the group are applied in each group to first respective inputs of a logic (NOT)-AND gate, a further respective input of each said logic (NOT)-AND gate in the group connected to the output of the preceding group, each group including an additional (NOT)-AND gate, one input of which is connected to said output of the preceding group and further inputs of which are connected to terminal means for providing the inverses of the interrogation signals, one of said groups including the output of each (NOT)-AND gate associated therewith connected to an input of a $(n+1)$ inputs of a 1-out-of- $(n+2)$ position device, wherein n is the number of lines in one group, and means connecting the $(n+2)$ th input of the 1-out-of- $(n+2)$ position device of one group to the output of the next following group for blocking said one group from interrogation signals during adjustment of a reset position.

2. A priority circuit as claimed in claim 1 wherein said 1-out-of- $(n+2)$ position device includes a $(n+2)$ (NOT)-AND gates, the outputs of said (NOT)-AND gates, receiving the interrogation signals and their inverses, being connected to the inputs of the multiplet so that the multiplet takes over the signal condition of the outputs of the said (NOT)-AND gates as a position of the 1-out-of- $(n+2)$ position device.

25 3. A priority circuit as claimed in claim 2 wherein in the case of $(n+1)$ AND gates as input gates of a group the multiplet circuit includes (NOT)-OR gates.
